Attorney

Patented July 24, 1928.

UNITED STATES PATENT OFFICE.

EDWIN J. HERCHERT, OF GUTTENBERG, IOWA.

CROSS MEMBER FOR NONSKID CHAINS.

Application filed March 5, 1927. Serial No. 173,124.

This invention relates to cross members for non-skid chains for automobile wheels or the like and it is an object of the invention to provide a cross member of this type 5 constructed in a manner whereby effective gripping action is had upon the roadway.

Furthermore, it is an object of the invention to provide a cross member constructed in a manner to operate effectively to prevent both skidding and slippage.

The invention consists in the details of construction and in the combination and arrangement of the several parts of my improved cross member for a non-skid chain 15 whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawing, wherein:—

Figure 1 is a fragmentary view in side elevation illustrating an anti-skidding device embodying cross members constructed in accordance with an embodiment of my invention;

Figure 2 is an enlarged transverse sectional view taken through the structure as illustrated in Figure 1;

Figure 3 is a view in top plan of one of the links as herein comprised within a cross member.

As disclosed in the accompanying drawing, my improved cross members M are operatively engaged with the side chains C.

40 Each of the cross members M comprises a plurality of links L, adjacent links being freely engaged or connected.

Each of the links L as herein set forth is formed from a single length of material and 45 embodies an inner bar 1 substantially in the form of a Z with the extremities of such bar

1 returned to provide the eye members 2 and continued by the arms 3. These arms 3 are longitudinally aligned and extend over the Z-bar 1 and have their extremities welded or otherwise fixedly secured to provide an outer straight bar. Each eye member 2 of a link L is freely interlocked with an eye member of an adjacent link and when in applied position the Z-bar 1 is in direct contact with the tire carcass T.

The Z-bar 1 of each of the links provides an effective medium to offset skidding while the outer straight bar provides an effective medium to offset slippage, thereby assuring effective gripping on the road surface.

From the foregoing description it is thought to be obvious that a cross member for a non-skid chain constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

A chain link consisting of a continuous strand formed in the general shape of a 80 loop, said loop having a Z-shaped side bar and a straight side bar, said bars being disposed in parallel planes, said strand having eyes formed at the ends of the loop, said eyes being disposed in the plane of the Z-shaped bar, and having at their inner sides laterally disposed shank portions which merge with the ends of the straight side bar.

In testimony whereof I hereunto affix my 90 signature.

EDWIN J. HERCHERT.
